US0D1052193S

(12) United States Design Patent (10) Patent No.: US D1,052,193 S
(45) Date of Patent: * Nov. 19, 2024

(54) DISPOSABLE DIAPER FOR PETS

(71) Applicant: Unicharm Corporation, Ehime (JP)

(72) Inventors: Yumi Koido, Kanonji (JP); Daisuke Komatsubara, Kanonji (JP)

(73) Assignee: Unicharm Corporation, Ehime (JP)

() Term: 15 Years

(21) Appl. No.: 35/518,510

(22) Filed: Oct. 6, 2022

(80) Hague Agreement Data

Int. Filing Date: Oct. 6, 2022

Int. Reg. No.: DM/224163

Int. Reg. Date: Oct. 6, 2022

Int. Reg. Pub. Date: Oct. 6, 2023

(30) Foreign Application Priority Data

May 16, 2022 (JP) 2022-010328

May 16, 2022 (JP) 2022-010329

(57) CLAIM

The ornamental design for a disposable diaper for pets as shown and described.

DESCRIPTION

1.1 : Perspective

1.2 : Front

1.3 : Back view, showing an uncut tail aperture

1.4 : Top

1.5 : Bottom

1.6 : Left

1.7 : Right

1.8 : Back view, showing a torn tail aperture

1.9 : Perspective view, showing a first condition of use

1.10 : Perspective view, showing a second condition of use

2.1 : Perspective

2.2 : Front

2.3 : Back view, showing an uncut tail aperture

2.4 : Top

2.5 : Bottom

2.6 : Left

2.7 : Right

2.8 : Back view, showing a torn tail aperture

2.9 : Perspective view, showing a first condition of use

2.10 : Perspective view, a second condition of use

Designs 1 and 2: both Embodiments are disposable diapers for pets. Uncut tail apertures are shown in 1.3 and 2.3; the diaper is altered by tearing the tail aperture as shown in

1.8-1.10 and 2.8-2.10. The broken lines depict portions of the disposable diaper that form no part of the claimed design. The dash-dot-dash broken lines define the boundaries of the claim and form no part thereof.

1 Claim, 20 Drawing Sheets
